DEVICE FOR POLISHING METAL OR
THE LIKE

Matt Ryan, Detroit, Mich.

Application January 31, 1935, Serial No. 4,277

10 Claims. (Cl. 51—193)

My invention relates to devices for polishing metal, or the like, preparatory to the application of plating or similar finish.

Polishing devices of the kind to which my invention relates, consist generally of wheels made up of superimposed layers or pads of fabric or fibrous material, such as cloth or felt or a like fibrous material, or of leather, the layers being usually secured together by intervening layers of adhesive material, such as glue, or the like. In such devices, the edges of the layers of fibrous material and adhesive material which are presented at the periphery or polishing face of the device, extend in circumferentially disposed and parallel alternating areas of relatively soft material composed of the cloth, and relatively harder material composed of the glue or adhesive between the cloth layers. A wheel so constructed is rotated past given points at which the article to be polished is applied, either manually or by means of a work holding device. The working face of the device is dressed off evenly by means of a file or like instrument, a coating of glue applied thereto, a coating of abrasive, such as emery dust, applied to the glue, and a second coating of glue applied over the abrasive material, and the device operated until the wearing face so applied is worn off, at which time the edge of the device is again dressed off evenly and a new coating of glue and abrasive material applied. The alternating relatively soft layers of cloth and relatively hard layers of glue provide alternating relatively soft and hard areas supporting the facing material, which results in ridging or uneven polishing, deeper polishing occurs at the point of contact opposite the relatively hard or more resistant areas. This objectionable condition also arises where the superimposed pads or layers making up the wheel are not joined by layers of hard adhesive material, but are joined by layers of adhesive as soft or softer than the fibrous material, or where no adhesive joining element at all is used and the pads are secured together by transversely extending bolts or pins or other similar means. In such cases where a soft joining material is used there is inevitably a difference in resistance presented by the fibrous material and the joining material which will cause ridging or uneven polishing if the layers present circumferentially parallel alternating layers. The same thing occurs where no joining material at all is used, as in the case where the pads are secured together by bolts or pins or the like, as there will be areas of relatively low resistance at the joints between ad-

jacent pads. In order to eliminate such ridging and uneven polishing, it is necessary for the operator to manipulate the work piece relative to the polishing surface by holding it in different angular positions relative thereto, and by wiping the work piece across the polishing surface from different angles. It requires considerable training and practice to do this successfully and, unless the workman is well skilled and long practiced, inferior work is the result.

There are also installations in which a number of polishing wheels are arranged at succeeding stations and to which the work is passed by automatically operated work handling machinery. In such installations, it is necessary, with the conventional polishing wheels of the type described, to dispose them in different angular positions along the line of the work so that a succeeding wheel will move across the work in a different path than the preceding wheel and eliminate the ridging or uneven polishing produced by the areas of different resistance of the preceding wheel. This presents a complicated and expensive arrangement for driving or operating the wheels and also for passing the work from wheel to wheel.

One object of my invention is to provide a polishing device of the type described, in which the relatively soft and relatively hard areas presented by the working surface of the device are so arranged as to eliminate scratching, ridging or uneven polishing, and also to make it unnecessary to manipulate the work piece relative to the working surface in order to prevent uneven polishing.

Another object of my invention is to provide a polishing device of the type described, which may be successfully operated by relatively unskilled workmen, which will effect a substantial saving in the polishing time required, and which will also eliminate many of the expensive and complicated arrangements necessary to operate a gang of polishing devices where it is desired to feed and manipulate the work by machinery, and which will eliminate, in many cases, the necessity of gangs wherein some wheels are used to correct the work of other wheels.

With the foregoing and other objects in view, my invention is illustrated in the combination, arrangement and construction of parts described in the following specification and claimed in the appended claims, and shown in the accompanying drawing, in which:

Figure 1 is a view in side elevation of a polishing wheel made according to my invention and

having a part of the side covering broken away to better illustrate the construction.

Fig. 2 is an edge view of my device, having part of the wearing face of glue and abrasive broken away to better illustrate the construction.

Fig. 3 is an enlarged fragmentary, sectional view taken on line 3-3 of Fig. 1.

Fig. 4 is a perspective view of one of the 10 like layers of cloth material used in the construction of my device.

Fig. 5 is a perspective view of another of the 15 layers of cloth material of different shape than Fig. 4, which is also used in the construction of my device.

Fig. 6 is an enlarged fragmentary edge view of my device, having parts broken away to better illustrate the construction.

The embodiment of my invention shown in the 20 drawing comprises a wheel, generally indicated by the numeral 1, which is made up of a number of super-imposed pads or layers of cloth fragments which are stitched together at spaced intervals, as indicated by the dotted lines in Fig. 25 4. These layers 2 are in the form of circular discs, Other layers 3 of a tapered and sector-like shape, as shown in Fig. 5, are also used; these pads or layers are also made up of cloth fragments stitched together at spaced intervals, as indicated 30 by the dotted lines. A number of these pads of cloth material, super-imposed upon one another, are required to make a wheel of a suitable thickness. It is necessary to build the wheel up in pads or layers owing to the difficulty of stitching 35 a single layer of cloth fragments of sufficient thickness to form the desired size of wheel.

In conventional wheels of this kind now in use, the wheel is made up of a series of flat discs, like that shown in Fig. 4. These discs are secured together by layers of glue or adhesive material 4, with the result that the peripheral edge of the wheel, which is the working face, presents a series of circumferentially extending and alternatively disposed relatively soft and relatively 45 hard areas or surfaces, the relatively soft areas being furnished by the edges of the cloth and the relatively hard areas being presented by the glue disposed between the cloth layers. Consequently, when the piece of work is held against the 50 peripheral surface of the revolving wheel, the glue edges will cause parts of the work to be more deeply polished than the edges of the cloth, and this is so even when the working face of glue and abrasive is applied to the periphery of the wheel. This working face consists of a layer of glue 5, a layer of abrasive such as fine emery dust 6, another layer of glue 5 and a final layer of emery dust 6. The relatively hard radially extending 55 layers of glue 4, which secure the alternative layers of cloth 2 and 3 together, present a more rigid backing for the working surface of glue and emery dust than do the edges of the cloth layers. Consequently, the polishing is more severe opposite the edges of the glue layers 4 than it is opposite the softer edges of the cloth layers 2 and 3. A like result occurs if the layers 4 of glue are softer or less resistant than the adjacent edges of the pads of material 2 and 3. In such case the deeper polishing would occur opposite the edges of the fibrous material. The same result occurs if the pads of fibrous material 2 and 3 are secured together by other means (not shown) such as transversely extending pins 75 or bolts inserted through the assembled pads

from side to side at points between the periphery and center of the wheel, or by clamps applied to the opposite sides of the wheel, and the glue or adhesive layers omitted, as in such cases there are areas of relatively low resistance opposite the joints between the pads, and the adjacent edges of the pads provided the areas of relatively high resistance which will cause deeper polishing at spaced points on the work. Thus, if the work piece is held against the periphery of the wheel 1 in a constant position, its surface will be unevenly polished. In order to eliminate this unevenness, it is necessary for the polisher to manipulate the work piece in different angular positions relative to the surface of the wheel in order 15 to obtain an evenly polished surface, and this requires long experience and practice to develop the necessary skill to produce acceptable work. It also requires a considerable amount of time.

I have eliminated this objectionable feature 20 by constructing my new wheel of a series of circular discs, such as 2 shown in Fig. 4, which are bent radially to form a series of undulations along the periphery of the discs as shown in Fig. 2. A number of these undulated discs are super-imposed upon one another, as shown in Fig. 2, and the depressions between the succeeding undulations are filled in with a series of super-imposed sector shaped pads, such as 3 shown in Fig. 5, whose side edges and apex are appropriately tapered and beveled to fit the curved surfaces of the undulated discs 2. When the wheel thus constructed, is built up to the desired width, I apply to each side thereof a flat annular disc 10 and to the outer sides of these annular discs 10 a canvas cover 11. The side discs 10 may be omitted, if desired.

The construction thus described and shown in edge view in Fig. 2, presents a working face in 40 which the curved or undulated layers 2 with their intervening layers of glue, intersect the straight lines of layers 3 and their intervening straight lines or layers of glue, and eliminate the uneven polishing which results when all of 45 the layers of cloth and their intervening layers of glue are disposed in parallel relation. This is effected as will be readily understood, by the fact that in the construction described, the relatively hard surfaces passed across the work by 50 the glue layers are alternately followed by the relatively soft surfaces presented by the cloth layers thus compensating for the different polishing effect produced by the different surfaces, or by areas of different resistance in the working 55 face of the wheel by reason of the laminated construction, and ultimately producing, without the necessity for manipulation of the work piece, a uniformly polished surface.

The same method of arrangement of the pads 6 or fibrous material layers is used where the intervening layers of adhesive material is as soft or softer than the fibrous material, and also where the pads are secured together without the intervening layers of adhesive. The polishing effect 6 produced is the same, and it is to be understood that such constructions are within the scope of my invention.

It is also to be understood that the term "fibrous material" as used in the specification and claims, is intended to include canvas, cloth, leather and felt or other compacted but unwoven fibers, all of which are at times used in constructing such wheels.

The construction described also helps prevent the layers or pads of fibrous material from bushing or spreading axially at the periphery of the wheel, as the ends of the pads 3 are secured or abutted against the curved surfaces of the pads 2, and the curvature of the pads 2 resists any diverging spread between them in an axial direction.

Formal changes may be made in the specific embodiment of the invention described without departing from the spirit and substance of the broad invention, the scope of which is commensurate with the appended claims.

What is claimed is:

1. A polishing wheel comprising, superimposed layers of relatively soft fibrous material secured together by intervening layers of relatively hard adhesive material, some of said layers being of circular, disc-like form sinuously curved relative to the periphery of said wheel, and others of said layers being sector shaped and fitted in the depressions formed on opposite sides of said curved layers.

2. A polishing wheel comprising, superimposed layers of relatively soft fibrous material secured together by intervening layers of relatively hard adhesive material, some of said layers being in the form of circular discs sinuously curved relative to the periphery of said wheel, and others of said layers being sector shaped and fitted in the depressions formed on opposite sides of said curved layers, and a flat circular disc-like layer secured on each side of said combined curved and sector-shaped layers.

3. A polishing wheel comprising, superimposed layers of relatively soft fibrous material secured together by intervening layers of relatively hard adhesive material, some of said layers having their peripheral edges sinuously arranged and traversing the width of the periphery of said wheel, and others of said layers being substantially uniplanar throughout and sectioned to fit in the depressions in said sinuously curved layers, all forming a flat sided wheel having a working periphery of uniform width.

4. A polishing wheel comprising, superimposed layers of relatively soft fibrous material secured together by intervening layers of relatively hard adhesive material with the edges of said layers arranged in axially spaced hard and soft areas at the periphery of said wheel, a central group of said layers having their peripheral edges sinuously curved from side to side of the periphery of said wheel, and others of said layers being fitted in the depressions at the sides of said sinuously curved layers and having their axially spaced hard and soft areas, interrupted by the

curved hard and soft areas presented by said central group of layers.

5. A polishing wheel comprising, superimposed layers of relatively soft fibrous material secured together by intervening layers of relatively hard adhesive material with the edges of said layers arranged in axially spaced hard and soft areas at the periphery of said wheel, and having the edges of some of said hard and soft layers reversely curved along the periphery of said wheel 10 and obliquely interrupting the edges of the other hard and soft layers.

6. A polishing wheel comprising, superimposed layers of fibrous material having the edges of said layers presented at the periphery of said 15 wheel, a central group of said layers having their peripheral portions sinuously curved axially from side to side at the periphery of said wheel, and others of said layers being sectioned and secured in the depressions at the sides of said 20 sinuously curved layers.

7. A polishing wheel comprising, superimposed layers of fibrous material having the edges of said layers presented at the periphery of said wheel, a central group of said layers having their peripheral portions sinuously curved from side to side of the working face of said wheel, and others of said layers being uniplanar and fitted and secured in the depressions at the sides of said 30 sinuously curved layers.

8. A polishing wheel comprising, superimposed layers of fibrous material having their edges presented at the periphery of said wheel, some of said layers having their peripheral portions sinuously curved along the working face of said wheel 35 and axially interrupting the edges of other and uniplanar layers.

9. A polishing wheel comprising superimposed layers of fibrous material, said layers being of circular, disc-like form sinuously curved relative 40 to the periphery of the wheel, and separate independent sectors of fibrous material fitting in the depressions formed on opposite sides of said layers to form a wheel having a working area of 45 uniform width.

10. A polishing wheel comprising superimposed layers of fibrous material, such layers being of circular, disc-like form sinuously curved relative to the periphery of the wheel, separate independent sectors of fibrous material fitting in the depressions formed on opposite sides of said layers to form an assembly of sinuously curved layers and sectors, and separate straight edged annular discs of fibrous material secured to opposite sides of said assembly of sinuously curved layers and 55 sectors, all forming a wheel having a working area of uniform width.

MATT RYAN.
